Albert H. Geilfuss

By *Frankdaaleman*

Attorney

UNITED STATES PATENT OFFICE.

ALBERT H. GEILFUSS, OF PARKERSBURG, WEST VIRGINIA.

NECKTIE HOLDER.

Application filed March 27, 1923. Serial No. 628,063.

To all whom it may concern:

Be it known that I, ALBERT H. GEILFUSS, a citizen of the United States of America, and resident of Parkersburg, in the county 5 of Wood and State of West Virginia, have invented certain new and useful Improvements in Necktie Holders, of which the following is a specification.

This invention relates to apparel, and 10 particularly to necktie fasteners.

An object of this invention is to produce a necktie fastener having means by which the necktie can be frictionally held through engagement of certain parts of the device 15 with the collar to which the necktie is applied; and the inventor furthermore includes novel means whereby the necktie is more firmly anchored in place through the provision of novel means engaging the 20 front collar button to which the collar is attached, so that by the use of the invention a three bearing or three point engagement occurs which will serve to prevent dislodgment of the necktie, while at the same 25 time it permits the necktie to be secured in place or removed without undue effort.

It is a further object of this invention to provide collar clamping elements and a button engaging element secured in super- 30 imposed relation, wherein the ends of the device for engaging the collar button are protected between the collar plates or engaging elements, the said elements being secured together by the process of spot 35 welding whereby the device can be expeditiously manufactured in a manner to insure such strength and durability at the joints, as will insure a successful operation of the device.

40 It is a further object of this invention to produce a necktie holder of the character indicated in which the ends of the collar button engaging device may be inserted in apertures of one or both of the clip members 45 prior to the welding operation, to insure further strength and durability.

With the foregoing and other objects in view, the invention consists in the details of construction, and in the arrangement and 50 combination of parts to be hereinafter more fully set forth and claimed.

In describing the invention in detail, reference will be had to the accompanying drawings forming part of this application 55 wherein like characters denote correspond-

ing parts in the several views, and in which—

Figure 1 illustrates a view in elevation of the rear of the necktie holder embodying the invention, the necktie fabric being 60 shown in dotted lines;

Figure 2 illustrates an edge view thereof;

Figure 3 illustrates a view in elevation embodying a slight modification;

Figure 4 illustrates a similar view embodying a still further modification;

Figures 5, 6 and 7 are enlarged detail views partly in section, showing the joint between the clip members and the button engaging device; and

Figure 8 illustrates a horizontal sectional view of a fragment of the clip, showing further modified means for anchoring a collar button engaging element.

In these drawings, 10 denotes one of the 75 clip elements and 11 the coacting element, which in operation are to be attached to a collar on each side of the opening at the front, the said clip members embracing the collar and being of such rigidity as to effectually clamp the collar to aid in retaining the necktie in place. Of course these elements must be somewhat resilient, and they must yield sufficiently to permit the insertion of a collar between them. The 80 necktie fabric may be formed after the manner of a bow tie or otherwise and secured to the outer clip element by appropriate fastening such as stitching or the like, inserted in the apertures 12. The apertures may 85 be increased or diminished, according to the requirements, but usually two or three apertures in each end will suffice, and under certain conditions, only one aperture may be formed at each end. The clip elements 90 and their relation to each other are the same in the forms shown in Figs. 2 and 3.

The button engaging device shown in Figs. 1 and 2 is formed of wire with certain portions of its length and its ends 13 and 14 100 inserted between the clip elements and secured to the clip elements by the process of spot welding, the joints 15 and 16 of which are illustrated in Fig. 5. The button engaging element has a loop portion 17 extending partially over the inner clip member 11 so that when the clip is applied to the collar, the button engaging loop may be inserted partially around the shank of the collar button and the button engaging element 110

will assist in retaining the necktie in position.

In that form of the invention shown in Fig. 3, the button engaging element 18 has its ends 19 and 20 inserted and seated in apertures such as 21 formed preferably in the inner leaf member, although, of course, they can be inserted in the outer leaf member, or one may be inserted in one leaf member and the other in another leaf member. This latter construction aids in strengthening the device to some extent as each end of the collar button engaging member would be more firmly anchored to a leaf member. This last mentioned embodiment of the invention is shown in Fig. 8.

Figure 4 shows a construction of the clip, and the means of anchoring the collar button engaging element 22 to it is the same as that heretofore described, except in this form the collar button engaging element has an inverted V-shaped bar 23, which under some conditions may be preferable, as it to a greater or less extent embraces the shank of the collar button.

In Fig. 8 the clip members 24 and 25 have apertures 26 and 27 respectively, and an end 28 of the collar button engaging member is seated in the recess 26 whereas the other end 29 of the collar button engaging member is seated in the aperture 27, and the members are secured together preferably by spot welding, as heretofore explained.

The structure just described will prove effective in preventing separation of the leaf members or their disengagement from the collar button engaging member.

I claim:

1. In a necktie holder, clip members adapt-

ed to embrace the edges of a collar at the front opening, a collar button engaging member having portions thereof and its ends inserted between the members and secured to said members by spot welding.

2. In a necktie holder, clip members, one of which has apertures, a collar button engaging member having portions inserted between the said clip members and having its ends seated in the said apertures, the said collar button engaging member and the said clip members being secured together by a binder.

3. In a necktie holder, clip members, one of which has apertures, a collar button engaging member having portions inserted between the said clip members and having its ends seated in the said apertures, the said collar button engaging member having a loop overlying one of the clip members, the loop portion thereof being the shape of an inverted V, the said collar button engaging member and the said clip members being secured together by a binder.

4. In a necktie retainer, clip members, each of which has an aperture, a collar button engaging element comprising a member having a loop portion adapted to partially embrace the shank of a button and having portions lying between the clips and terminating in angularly disposed ends, one of which is inserted in an aperture of one of the clips and the other of which is inserted in the aperture of the other clip, the said clip members and button engaging member being secured together, as and for the purpose set forth.

ALBERT H. GEILFUSS.
